(57) **CLAIM**

The ornamental design for a lighter, as shown and described.

DESCRIPTION

FIG. 1 is a front perspective view of a preferred embodiment of the lighter according to the present design;

FIG. 2 is a front perspective view of another preferred embodiment of the lighter according to the present design;

FIG. 3 is a front perspective view of another preferred embodiment of the lighter according to the present design;

FIG. 4 is a front perspective view of another preferred embodiment of the lighter according to the present design;

FIG. 5 is a front perspective view of another preferred embodiment of the lighter according to the present design;

FIG. 6 is a front perspective view of another preferred embodiment of the lighter according to the present design;

FIG. 7 is a lower perspective view of the lighter of FIG. 1, illustrating a cutter of the lighter in an open position;

FIG. 8 is a front elevational view of the lighter of FIG. 1;

FIG. 9 is a rear elevational view of the lighter of FIG. 1;

FIG. 10 is a right-side elevational view of the lighter of FIG. 1;

FIG. 11 is a left-side elevational view of the lighter of FIG. 1;

FIG. 12 is a top plan view of the lighter of FIG. 1;

FIG. 13 is a bottom plan view of the lighter of FIG. 1;

FIG. 14 is a front perspective view of another preferred embodiment of the lighter according to the present design;

FIG. 15 is a front perspective view of another preferred embodiment of the lighter according to the present design;

FIG. 16 is a front perspective view of another preferred embodiment of the lighter according to the present design;

FIG. 17 is a front perspective view of another preferred embodiment of the lighter according to the present design; FIG. 18 is a front perspective view of another preferred embodiment of the lighter according to the present design; FIG. 19 is a front perspective view of another preferred embodiment of the lighter according to the present design; FIG. 20 is a front elevational view of the lighter of FIG. 14; FIG. 21 is a rear elevational view of the lighter of FIG. 14; FIG. 22 is a right-side elevational view of the lighter of FIG. 14; FIG. 23 is a left-side elevational view of the lighter of FIG. 14; FIG. 24 is a top plan view of the lighter of FIG. 14; FIG. 25 is a bottom plan view of the lighter of FIG. 14; FIG. 26 is a front perspective view of another preferred embodiment of the lighter according to the present design; FIG. 27 is a front perspective view of another preferred embodiment of the lighter according to the present design; FIG. 28 is a front perspective view of another preferred embodiment of the lighter according to the present design; FIG. 29 is a front perspective view of another preferred embodiment of the lighter according to the present design; FIG. 30 is a front perspective view of another preferred embodiment of the lighter according to the present design;

FIG. 31 is a front perspective view of another preferred embodiment of the lighter according to the present design; FIG. 32 is a lower perspective view of the lighter of FIG. 26, illustrating a cutter of the lighter in an open position; FIG. 33 is a front elevational view of the lighter of FIG. 26; FIG. 34 is a front perspective view of another preferred embodiment of the lighter according to the present design; FIG. 35 is a front perspective view of another preferred embodiment of the lighter according to the present design; FIG. 36 is a front perspective view of another preferred embodiment of the lighter according to the present design; FIG. 37 is a front perspective view of another preferred embodiment of the lighter according to the present design; FIG. 38 is a front perspective view of another preferred embodiment of the lighter according to the present design; FIG. 39 is a front perspective view of another preferred embodiment of the lighter according to the present design; and, FIG. 40 is a front elevational view of the lighter of FIG. 34. The broken line showing is for illustrative purposes only and forms no part of the claimed design.
